UNITED STATES PATENT OFFICE

JOHN L. DRAKE, OF TOLEDO, OHIO, ASSIGNOR TO LIBBEY-OWENS-FORD GLASS COMPANY, OF TOLEDO, OHIO, A CORPORATION OF OHIO

CAR OR TABLE TRANSFER MEANS

Application filed June 18, 1931. Serial No. 545,354.

This invention relates to the grinding and polishing of sheet or plate glass or other flat sheets or plates to be surfaced, and more especially to an apparatus for this purpose of the so-called continuous type.

Various systems for the continuous grinding and polishing of plate glass have heretofore been proposed and in practically all of such systems there have been provided

- 10 a series of cars or tables mounted upon wheels and adapted to be rolled along tracks in a continuous train first under a series of grinding units and then under a series of polishing units.
- 15 In the particular arrangement to which the present invention is applied, three substantially parallel tracks are employed, the two outside tracks being working tracks for carrying the work cars or tables beneath a series 20 of grinding and polishing runners and the single central track constituting the return track for bringing the cars or tables back to their starting position on the working tracks.

The primary object of the present invention is the provision of improved means for facilitating the handling of the cars or tables and more particularly for effecting the transfer of said tables from the working tracks to the return track or vice versa in a rapid and efficient manner.

Another object of the invention is the provision of novel transfer means of the above character which is of a simplified form and wherein the transfer of the tables from one track to another track may be readily and conveniently effected with rapidity and ease of operation.

A further object of the invention is the provision of novel transfer means of the above character including a plurality of transfer cars or tables located at one or both ends of the tracks, the return track being disposed at a relatively lower level than the working tracks, and the transfer cars at each end of said tracks being counter-balanced in such a manner that a minimum amount of power is required for effecting the movement thereof between the three tracks.

Other objects and advantages of the invention will become more apparent during the

course of the following description when taken in connection with the accompanying drawings.

In the drawings forming a part of this application and wherein like numerals are employed to designate like parts throughout the same,

Fig. 1 illustrates diagrammatically a plan view of transfer means provided by the present invention,

Fig. 2 is an end elevation thereof,

Fig. 3 is a section taken substantially on line 3—3 of Fig. 2, and

Fig. 4 is a section taken substantially on line 4—4 of Fig. 1.

The system disclosed in the drawings includes the three substantially parallel tracks 5, 6 and 7, the two outside tracks 5 and 6 constituting the working tracks and the single central track 7 constituting the return track. These tracks are adapted to carry a series of work cars or tables 8 upon the upper surfaces of which are positioned the glass sheets to be ground and polished, said tables being supported upon wheels 9 which roll along the said tracks.

In practice, the glass sheets to be surfaced are adapted to be secured upon the cars 8 at one end of working tracks 5 and 6 and are then carried along these tracks first beneath a series of grinding runners and then beneath a series of polishing runners, the tables being preferably coupled together to form a continuous train as is well known in the art. When the tables reach the opposite ends of the working tracks 5 and 6, the glass sheets are removed therefrom and the said cars are uncoupled and transferred to the return track 7 along which they are moved to the starting end of the working tracks.

The present invention contemplates the provision of improved transfer means between the tracks 5, 6 and 7 at one or both ends thereof for transferring the cars from the working tracks to the return track or vice versa. As illustrated in the drawings, the working tracks 5 and 6 are arranged in horizontal alignment with one another while the return track 7 is disposed at a relatively lower level and also on a different plane

horizontally which is preferably beneath the floor level 10. Positioned at each end of the tracks 5, 6 and 7 is a pit 11 substantially in line with the return track 7, and leading upwardly from opposite sides of the pit are the inclined rail beds 12 and 13 upon which are mounted the transverse transfer tracks 14 and 15 respectively, it being noted in Fig. 1 that one of the tracks, and as here shown 10 track 14, is of a relatively narrower gauge than track 15.

Mounted to run along the transverse tracks 14 and 15 are the transfer cars 16 and 17 respectively, each being supported upon wheels 18 engaging the said tracks. The transfer cars are so constructed that the upper surfaces thereof will at all times maintain a horizontal position during their movement along the inclined tracks 14 and 15. The 20 transfer cars 16 and 17 carry track sections 19 and 20 respectively which are adapted upon movement of the said cars to line up with the working tracks and return track.

The transfer cars 16 and 17 are preferably 25 connected together in such a manner that they counter-balance one another, said connection including a pair of chains 21 and 22 which are attached at one end to the transfer car 16 as at 23 and at the opposite end to the car 17 as at 24. The said chains 21 and 22 are each trained about four sprockets 25, 26, 27 and 28 mounted upon shafts 29, 30, 31 and 32 respectively. One of these shafts, and as here shown shaft 30, is preferably 30 positively driven such as from a motor 33 driving through suitable speed reduction gearing located in casing 34, a shaft 35 to which is keyed bevel gear 36 meshing with a corresponding bevel gear 37 fixed to shaft 30. 35 The chains 21 and 22 are of such a length that when one transfer car is in position opposite one of the working tracks, the other car will be in position opposite the return track as illustrated in Fig. 2. By counterbalancing 40 the transfer cars 16 and 17, it will be readily apparent that they can be moved along the inclined tracks 14 and 15 easily and conveniently and with the expenditure of a minimum amount of power. Moreover, the 45 above-described means for shifting the transfer cars between the several tracks 5, 6 and 7 is of a simplified form and involves no complicated or expensive mechanism which is very apt to frequently get out of order, such 50 as has been ordinarily employed in the past.

The means for moving the work tables 8 from the working tracks 5 and 6 onto the transfer cars 16 and 17 comprises an endless drag chain 38 positioned between the rails of 60 each of said tracks. Each drag chain comprises a plurality of pivotally associated links 39 connected together by shafts 40 in endless formation, said shafts also carrying rollers 41 which are supported during the upper 65 horizontal run of the chain upon rails 42.

The drag chain passes around a pair of sprockets 43 at the ends of the rails 42 and carries one or more dogs 44 which engage the rear ends of the tables and move the same forwardly from the working tracks onto the track sections 19 or 20 of the transfer cars 16 or 17 respectively. 70

The means herein provided for moving the work tables 8 from the transfer cars 16 and 17 onto the return track 7 consists of an overhead pusher arrangement 45 comprising an endless chain 46 trained about sprockets 47 and 48 which are carried upon shafts 49 and 50 respectively journaled in brackets 51 and 52 mounted upon the horizontal supporting beams 53. Also carried by the endless chain 46 are a pair of spring actuated plungers 54 constituting the pusher members which are adapted to engage the rear of the tables and effect movement thereof forwardly from the transfer cars onto the return track. 85

In carrying the present invention into practice, the transfer car 16 at one end of the system is adapted to receive the work tables 8 from working track 5 and deliver them to the return track 7, while the transfer car 17 is provided to receive the cars from working track 6 and deliver them to return track 7. At the opposite end of the system, the transfer cars 16 and 17 will receive the work tables 90 from the return track 7 and shift them into position opposite the working tracks 5 and 6 respectively. When the transfer car 17 is in a position to receive a work table from track 6, the transfer car 16 is in a position to deliver 95 one of the work tables previously received from working track 5 onto return track 7. As shown in Figs. 1 and 2, one of the tables 8 is being moved onto the transfer car 17 while, at the same time, a table is being delivered from 100 car 16 onto return track 7. The work table 8 is being moved onto transfer car 17 by means of the endless drag chain 38 and simultaneously the overhead pusher arrangement 45 is being operated to propel the table from the 105 transfer car 16 onto the return track 7. After the table 8 is on car 17 and the table removed from car 16, the motor 33 is placed in operation to rotate the sprockets 25 to 28 in a clockwise direction, whereupon the empty transfer car 16 will be pulled upwardly along the inclined track 14 to a position in alignment with working track 5 while, at the same time, car 17 will be moved downwardly along inclined track 15 into the pit 11 and into registry with the return track 7. When the position of the transfer cars is thus reversed, a table can be delivered from track 5 onto car 16 and simultaneously the table on car 17 can 110 be moved onto the return track. 120

It is to be understood that the form of the invention herewith shown and described is to be taken as the preferred embodiment of the same, and that various changes in the shape, size and arrangement of parts may be resorted 130

to without departing from the spirit of the invention or the scope of the subjoined claims.

I claim:

1. The combination with a plurality of substantially parallel tracks, and a series of work tables movable along the same, of a plurality of transfer cars provided at one end of said tracks and by means of which the said tables may be transferred from one track to a second track, said transfer cars being counter-balanced and each being movable between two of said tracks.

2. The combination with a plurality of substantially parallel tracks, and a series of work tables movable along the same, of a pair of transfer cars provided at one end of said tracks and by means of which the said tables may be transferred from one track to a second track, and means for connecting said transfer cars together so that they counter-balance one another, with each car being movable between two of said tracks.

3. The combination with three substantially parallel main tracks, and a series of work tables movable along the same, of a pair of tracks arranged transversely of the first-mentioned tracks at one end thereof, each transverse track extending between the center main track and one outside main track, and transfer cars movable along said transverse tracks and by means of which the said tables may be transferred from one main track to a second main track.

4. The combination with three substantially parallel main tracks, and a series of work tables movable along the same, of a pair of tracks arranged transversely of the first-mentioned tracks at one end thereof, each transverse track extending between the center main track and one outside main track, and transfer cars movable along said transverse tracks and by means of which the said tables may be transferred from one main track to a second main track, said transfer cars being counter-balanced and each being movable between two of said parallel tracks.

5. The combination with three substantially parallel main tracks, and a series of work tables movable along the same, of a pair of tracks arranged transversely of the first-mentioned tracks at one end thereof, each transverse track extending between the center main track and one outside main track, a pair of transfer cars movable along said transverse tracks and by means of which the said tables may be transferred from one main track to a second main track, and means for connecting said transfer cars together so that they counter-balance one another, with each car being movable between two of said parallel tracks.

6. The combination with three substantially parallel main tracks, and a series of work tables movable along the same, the center track being disposed beneath the level

of the two outside tracks, of a pair of tracks arranged transversely of the first-mentioned tracks at one end thereof, each transverse track inclining upwardly from the center main track to one outside main track, and transfer cars movable along said transverse tracks and by means of which the said tables may be transferred from the center main track to one outside main track or vice versa.

7. The combination with three substantially parallel main tracks, and a series of work tables movable along the same, the center track being disposed beneath the level of the two outside tracks, of a pair of tracks arranged transversely of the first-mentioned tracks at one end thereof, each transverse track inclining upwardly from the center main track to one outside main track, and transfer cars movable along said transverse tracks and by means of which the said tables may be transferred from the center main track to one outside main track or vice versa, said transfer cars being counter-balanced.

8. The combination with three substantially parallel main tracks, and a series of work tables movable along the same, the center track being disposed beneath the level of the two outside tracks, of a pair of tracks arranged transversely of the first-mentioned tracks at one end thereof, each transverse track inclining upwardly from the center main track to one outside main track, a pair of transfer cars movable along said transverse tracks and by means of which the said tables may be transferred from the center main track to one outside main track or vice versa, and means for connecting said transfer cars together so that they counter-balance one another.

Signed at Toledo, in the county of Lucas and State of Ohio, this 13th day of June, 1931.

JOHN L. DRAKE.
